Application July 5, 1941, Serial No. 401,237
In Switzerland July 5, 1940

2 Claims. (Cl. 177—353)

The invention relates to a new and improved remote control installation operating according to the impulse method for the remote control of definite operations such as the switching on and off of signalling devices and so on. The invention relates more particularly to installations of the said type in which the performance of the desired operations is made dependent on the simultaneous occurrence of two alternating currents of different frequency.

The main object of the invention consists in the provision of improved safety methods and of means to avoid incorrect operations caused by foreign or disturbing impulses.

According to the present invention the said object is attained by a remote control installation in which the carrying-out of a desired operation is made dependent on the simultaneous occurrence of two alternating currents of different frequency, whereby the performance of an operation is controlled by a current impulse of one of the said alternating currents and of a time interval in the sequence of impulses of the other alternating current.

In the accompanying drawing there is shown by way of example one constructional form or embodiment of the invention on a remote control installation.

Fig. 1 shows in a diagram the displacement of the impulses,

Fig. 2 illustrates the connections in a diagrammatical manner.

The installation shown comprises a sending station I and a receiving station II. The sending station I comprises a relay arrangement consisting of a transmitter start key ST, a reset key RT, a relay A with make contacts a_1 , a_2 and a break contact a_3 , a relay B with a make contact b_1 , and a condenser K and resistances W_1 , W_2 to cause a time lag, a relay C with a break contact C_1 , and a relay B with a make contact d_1 . The contacts a_3 , d_1 control circuits 1, 2, which are connected with the transmitting line 3. One of said circuits is an open circuit and the other a closed circuit. In the circuit 1 are an alternating current generator Q_1 of frequency f_1 and a band filter X_1 . The circuit 2 comprises an alternating current generator Q_2 of frequency f_2 , and a band filter X_2 .

The relay arrangement at the receiving station II comprises an open circuit relay E with a make contact e_1 , a closed circuit relay G with a make contact g_1 , a relay H with a change-over contact h_1 and two break contacts h_2 , h_3 , a relay J with a changeover contact i_1 , a make contact i_2 and a condenser K' . There is also a resistance W_3 to

produce a time-lag, a final relay K with a change-over contact k_1 and a make contact k_2 , a relay L with a change over contact l_1 and a break contact l_2 , a relay M with a change-over contact m_1 and a make contact m_2 , a condenser K_2 and resistances W_4 , W_5 to produce a time-lag, and a reset key RT₁, as well as a signalling device O. The relays E and G are each connected through band filters Y_1 and M_2 respectively with the line 3.

10 The connection of the individual switching elements of the remote control installation shown appears directly from the drawing and need not be described in detail.

The installation shown in the drawing is ready 15 for operation. The diagram of impulses, Figure 1, illustrates that for an operation to be carried out there is required an impulse of the open circuit current T_1 of frequency f_1 and at the same time an interval between the impulses of a permanent current T_2 of frequency f_2 .

To start an operation, the key ST at the sending station I is pressed, thereby de-energizing relay A. By de-energizing relay A, the contacts a_1 , a_2 are opened and the closing of circuit contact a_3 is effected. By opening the contact a_3 the relay C is de-energized at once and, owing to the lagging condenser K and the resistances W_1 , W_2 , the de-energizing of the relay B occurs slowly. The contact c_1 of the relay C will be closed at once and the contact d_1 opened. The latter is closed again as soon as the contact b_1 is opened corresponding to the retarded drop of relay B. Therefore, the flow of alternating current in the line 3 of the frequency f_2 is interrupted for a short time. When the relay A is de-energized, the contact a_3 is closed and therewith alternating current of a frequency f_1 passes to the receiver II at the moment of opening the key ST. By pressing the key ST an alternating current impulse of the frequency f_1 will be transmitted and simultaneously the permanent alternating current of the frequency f_2 will be interrupted for a short time interval.

45 When an alternating current impulse of the frequency f_1 arrives at the receiver station II, the relay E is energized and the contact e_1 is closed. The interval in a sequence of impulses of the current of the frequency f_2 effects the de-energizing of the relay G. The contact g_1 is opened and therewith the relay H de-energized. The change-over contact h_1 is operated and the contacts h_2 , h_3 are closed. By changing over the contact h_1 , the relay M will be slowly energized by the condenser K_2 and the resistances W_4 , W_5 , and by

closing contact h_2 the relay L will be quickly energized by means of the elements l_1, h_2, RT_1 .

The relay L which has been energized moves the contact l_1 and l_2 respectively to make and break positions. The relay J is at the same time energized and changes-over the contact i_1 and closes contact i_2 . The relay J is rapidly energized, but the circuit of the relay is then immediately interrupted by movement of contact l_2 to break position. The relay J is not deenergized instantaneously, but slowly, due to the action of the condenser K_1 and the resistance W_1 .

If during the time interval between two impulses of frequency f_2 , corresponding with the time delay action of the relay J , an impulse of the frequency f_1 is received by the receiver, the relay H will be energized, thereby closing the circuit comprising contacts h_1, i_2, e_1, k_1 , and relay K . The relay K is thus energized and its contact k_1 changed over and the contact k_2 closes the circuit for the device to be controlled.

The operation cannot be effected if the permanent current of the frequency f_2 does not arrive at the receiver II at the predetermined time. The alternating current of the frequency f_2 arriving too late cannot close the circuit of the relay K as the contact h_1 has been switched in after the relay J has been de-energized.

If the sustained current of the frequency f_2 does not arrive at the predetermined time, the relay M will change-over the contact m_1 and the contact m_2 will be closed. The action of the relay M is retarded owing to the condenser k_2 and the resistances W_4, W_5 the time lag corresponds with the time interval of the impulses. The signalling device O is thereby energized to signal a disturbance.

By striking the keys RT, RT_1 at the end of a signalling operation all the elements return to their initial position shown in Figure 2 of the drawing in which the system is shown ready for operation.

What I claim is:

1. In a remote control apparatus, adapted for actuation by alternating current impulses of different frequencies, one a normally sustained current interrupted for a determined period to vary its action and the other a current produced during such period of interruption of the sustained

current, a receiver including in combination a signal circuit, a pair of primary relays, one being normally energized by the sustained current impulses of one of the frequencies and deenergized during the period of interruption thereof and the other being normally deenergized and adapted to be energized by the impulses of the current of the other frequency, said signal circuit being normally open, and means for closing the signal circuit when the relays are respectively deenergized and energized in timed order governed by the interruption period, said means including a normally open circuit normally disconnected from the signal circuit, a contact operated when the second named primary relay is energized to partly close and render said normally open circuit operative when closed, and a system of circuits adapted to be energized when the first named primary relay is deenergized and having controlling relays therein for closing the normally open circuit and connecting it with the signal circuit during a period of time governed by and corresponding to the time period of interruption of the sustained current impulses.

2. In a remote control apparatus, the combination of a transmitter provided with means for transmitting permanent current impulses of one frequency, means for interrupting the transmission of such impulses for a definite period of time, and means for transmitting current impulses of a different frequency during the time period of interruption of the first named frequency, and a receiver having a signal means therein, means responsive to the first named current impulses for normally rendering the receiver inoperative to actuate the signal means, means responsive to the second named current impulses during the interruption period of the first named current impulses for setting the receiver into action to operate the signal if a current impulse of the first named frequency is received before the end of the period of time from the inception of the interruption, and means for rendering the receiver inoperative to operate the signal means in the absence of and in the event that an impulse of the first frequency is not received within the given period of time from the inception of the interruption.

LEONHARD FINCKH.
